UNITED STATES PATENT OFFICE

157,642

WINDOW VENTILATING FAN OR THE LIKE

Ottis A. Sutton, Wichita, Kans., assignor to The
O. A. Sutton Corporation, Inc., Wichita, Kans.,
a corporation of Kansas

Application May 12, 1949, Serial No. 2,617

Term of patent 14 years

(Cl. D62—4)

To all whom it may concern:

Be it known that I, Ottis A. Sutton, a citizen of the United States, residing at Wichita, in the county of Sedgwick and State of Kansas, have invented a new, original, and ornamental Design for a Window Ventilating Fan or the like, of which the following is a specification, reference being had to the accompanying drawings, forming part thereof.

In the drawings:

Figure 1 is a front elevational view of a window ventilating fan, showing my new design, with the fan element thereof in one position;

Figure 2 is a rear elevational view of the same;
Figure 3 is a plan view of the same;

Figure 4 is a side elevational view of the same;

Figure 5 is a front elevational view showing my new design, with the fan element thereof in an alternate position; and

Figure 6 is a plan view of my new design when the fan element thereof is in the position shown at Figure 5.

I claim:

The ornamental design for a window ventilating fan or the like, as shown and described.

OTTIS A. SUTTON.
